(74) *Attorney, Agent, or Firm* — Gardner, Linn, Burkhardt & Ondersma LLP

(57) **CLAIM**

The ornamental design for the chair, substantially as shown and described.

DESCRIPTION

FIG. 1 is a perspective view of a chair showing the present invention;

FIG. 2 is a front elevation view of the chair of FIG. 1;

FIG. 3 is a left-side elevation view of the chair of FIG. 1;

FIG. 4 is a rear elevation view of the chair of FIG. 1;

FIG. 5 is a right-side elevation view of the chair of FIG. 1;

FIG. 6 is a top plan view of the chair of FIG. 1; and,

FIG. 7 is a bottom plan view of the chair of FIG. 1.

The broken lines shown are included for the purpose of illustrating environment of the design and form no part of the claimed design.

1 Claim, 4 Drawing Sheets
